CLAIM

The ornamental design for a hair clipper bladeset as shown and described.

DESCRIPTION

FIG. 1 is a top perspective view of the present hair clipper bladeset;

FIG. 2 is a right side view of the hair clipper bladeset of FIG. 1;

FIG. 3 is a left side view of the present hair clipper bladeset;
FIG. 4 is a front view of the hair clipper bladeset of FIG. 1;
FIG. 5 is a rear view of the hair clipper bladeset of FIG. 1;
FIG. 6 is a top plan view of the present hair clipper bladeset;
and

FIG. 7 is a bottom view of the hair clipper bladeset of FIG. 1;

FIG. 8 is a bottom perspective view of the hair clipper bladeset of FIG. 1;

FIG. 9 is an enlarged, fragmentary bottom perspective view of the bladeset of FIG. 8;

FIG. 10 is a top perspective view of the hair clipper bladeset of FIG. 1;

FIG. 11 is an enlarged, fragmentary top perspective view of the bladeset of FIG. 10;

FIG. 12 is a further bottom front perspective view of the hair clipper bladeset of FIG. 1;

FIG. 13 is an enlarged, fragmentary bottom front perspective view of the bladeset of FIG. 12;

FIG. 14 is a further top front perspective view of the hair clipper bladeset of FIG. 1; and,

FIG. 15 is an enlarged, fragmentary top front perspective view of the bladeset of FIG. 14.
